UNITED STATES PATENT OFFICE.

JAMES TIBURCE FELIX CONTI, OF PARIS, FRANCE.

COMPRESSED-AIR LOCOMOTIVE-CARRIAGE.

SPECIFICATION forming part of Letters Patent No. 673,978, dated May 14, 1901.

Application filed September 9, 1895. Serial No. 561,909. (No model.)

To all whom it may concern:

Be it known that I, JAMES TIBURCE FELIX CONTI, of the city of Paris, France, have invented Improvements in Compressed-Air Locomotive-Carriages, of which the following is a full, clear, and exact description.

This invention relates to a compressed-air locomotive-carriage specially arranged with a view to simplicity, compactness, and the utilization of compressed air in the most efficient manner.

This invention consists in the combination and arrangement of parts hereinafter described and claimed.

15 The engine, which is carried upon a framing of suitable construction, comprises two cylinders of different diameters for compound working, but capable of simple working when increased power is required, in which case the system of distribution forming the subject of previous Letters Patent, No. 554,111, dated February 4, 1896, granted to me may be employed. Reversing is effected by admitting compressed air to one or other side of a small auxiliary 20 piston which actuates the slide-valves. The compressed air is preferably heated before it enters each of the cylinders by means of small heaters having a large surface heated by a separate furnace under forced draft of air injected from the exhaust. The admission of compressed air is regulated so as to obtain any desired speed of the driving-pistons at all times by means of a Meyer expansion-gear in order that the compressed air may do its 25 work in the most efficient manner. The compressed-air reservoirs are charged at certain points of the journey by means of my improved automatic feed apparatus forming the subject of a former patent, No. 531,511, granted to me December 25, 1894.

Reference is to be had to the accompanying drawings, in which—

Figure 1 is a side elevation of the framing which carries the engines. Fig. 2 is a diagrammatic view showing the compressed-air distribution to the various parts. Fig. 3 is a plan view, partly in section, of the engine system in position upon the carriage.

The same characters of reference denote 30 like parts in all the figures.

A suitable engine-frame *a* of the under carriage carries the engines and other parts of

the mechanism, and a second frame *b* carries the body of the vehicle and the compressed-air reservoirs hung from the under side of the floor. The engines are carried by a single frame *c*, carrying the cross-head guides *d d*, one end of the frame being supported by two bearings upon the axle *e* (see Fig. 1) and the other upon a spring *f* on the frame *a* or directly upon the said frame. Upon axle *e* is keyed a toothed wheel *g*, driven by a pinion *g'*, keyed on the crank-shaft *h*, turning in bearings *i*, carried by frame *c*, and having two cranks *x* at ninety degrees operated by the two pistons. The speed of the engines with regard to the vehicle-wheels therefore depends upon the ratio of the gear *g g'*, which is inclosed in a dust-tight casing, and may run in a bath of oil. The cylinders *k l* are of different diameters to admit of compound working by the smaller cylinder exhausting into the larger cylinder. When, however, extra power is required or in case the small piston be at the dead-point at starting, the pressure may be admitted directly to both cylinders by a special arrangement of cocks.

The compressed air is supplied to the reservoirs *m* by means of the self-acting feed apparatus forming the subject of a previous patent, No. 531,511, granted to me on the 25th day of December, 1894. The compressed air before admission to the cylinders is heated by passing through the heaters *o' o''*, of suitable construction. The furnace-gases after having traversed each of the heaters *o' o''* are expelled by means of a forced draft produced by the exhaust-air from the engines, for which purpose the exhaust from each of the cylinders after being expanded is conducted through a suitable pipe into a pipe of the last heater *o''*, which receives the furnace-gases. The gases are thus discharged continuously into the atmosphere, since the exhaust-air is also continually escaping, owing to its expansion in the chamber, thus preventing shocks and reducing the velocity of the escaping air. When the engines are not working, a draft of air is obtained by a jet of compressed air supplied by suitable means. The distribution of compressed air to the various parts is effected by the following means:

In Fig. 2, *A'* is a vertical shaft operated from a hand-wheel shaft *A''* on the driver's plat-

form through an endless chain. Upon shaft A' are keyed two toothed sectors S' S² and a cam K, all the different adjustments being performed during a complete turn of shaft A'.
 5 The sector S', by which through the pinions p' p² p³ p⁴ p⁵ the Meyer expansion-valve of the high-pressure cylinder k is adjusted, requires only half a turn to shift the expansion-valve from one extreme to the other, leaving two-
 10 fourths of a revolution, of which one is required by the cam K to operate the brakes and the other by the sector S² for changing from compound to direct working, as follows: When on shaft A' being rotated in the direction of the arrow F' the last tooth of sector S' escapes from pinion p', the first tooth of sector S² engages in pinion p⁶. By still continuing to turn the shaft in the same direction the pinion p⁶ will be rotated and the crank-pin B' 20 will describe a half-circle, carrying with it the slide-valve T'. In the position shown the pipe C', and consequently space M behind the piston P', is open to the air through port O. The slide-valve T' will thus be held toward
 25 the right by the difference of pressure on the pistons P' P² of unequal area. This position corresponds to compound working, the exhaust from small cylinder k passing by pipe E' to the slide-valve T' and thence by pipe I' through the reheater o² to the valve-chest of the large cylinder l.
 When slide-valve T' is shifted by the sector S², it first cuts off communication of pipe C' with the air and then gradually uncovers
 35 the orifice of the pipe to allow compressed air admitted at C³ to pass directly thereto and thence through pipe C² to the space M behind the piston P'. The effect of the pressure is to suddenly shift the slide-valve T' over to
 40 the left-hand position. In this position the pipe C' communicates with I', and the exhaust-pipe E' from the small cylinder communicates with E², leading to the exhaust-chamber, through which the small cylinder k
 45 exhausts to the open air at the same time that the direct air-pressure admitted by valve T' passes through I' and reheater o² to the valve-chest of the large cylinder l. The upper end of the pipe C' may be of triangular
 50 form, so that each position of the slide-valve T' corresponds to a different area of admission to the large cylinder. Thus it will be seen that the farther the sector S² moves in the direction of the arrow F' the greater the admission to the large cylinder. In other words,
 55 the driver after having changed the working from compound to direct still has under control the admission to the large cylinder, which he can vary at will. When the crank-pin B'
 60 reaches the end of its course, the sector S' meets a stop, which limits the rotation of the hand-wheel. By turning the hand-wheel shaft A², and consequently the shaft A', in a direction opposite to that indicated by the arrow the opposite effects are produced—that is to say, the crank-pin B' returning to the position shown the valve T' cuts off direct

admission and opens the pipe C' to the air. The valve T' being no longer under the action of pressure within chamber M is caused to 70 suddenly assume the position shown by reason of the difference of area of the pistons P' P². When by the continued motion of the shaft A' in this direction the sector S' quits the pinion p', the lugs which regulate the cut-off 75 are at their maximum distance apart, so that the valve-chest is closed against any admission whatever either to the small or large cylinder. By still continuing to turn the hand-wheel in this direction the cam K acts 80 on friction-roller G of the lever L, and thus actuates the brake-regulator 41, whereby pressure is admitted to the brake-cylinders gradually and under the control of the hand-wheel. It will be understood that the cam 85 K, sectors S' and S², and the parts which co-operate with each of these elements are on different horizontal planes in order not to interfere with the action of one another. It will thus be seen that the whole of the mechanism can be controlled by the one shaft A', since during its passage from one extreme position to the other the following operations are performed in succession:
 90

By turning the hand-wheel in the direction of the arrow F', first, the cam K quits the friction-roller G, thus releasing the brakes; second, the sector S' engages the pinion p', thus gradually opening the admission of air to the small cylinder by acting on the lugs of the expansion-valve, the working being compound, and, third, the admission to the small cylinder being completely open the sector S² engages the pinion p⁶, whereupon the working is suddenly changed to direct, and while the 100 admission to the small cylinder remains open that to the large cylinder is opened gradually. Complete control is thus obtained, it being understood that by turning the shaft in the opposite direction the same effects are produced in the inverse order.
 105

For greater safety and to enable a sudden stoppage in case the chain or other part of the gear from the hand-wheel should fail a safety apparatus N is provided, which is controlled by a small cock R, placed within reach of the driver, whereby to enable the communication of the cylinders with the compressed-air supply to be suddenly cut off. It consists of a cylinder containing piston P³ on the 115 stem of a valve C⁶, held to its seat C⁵ in the position shown by pressure behind the piston P³, admitted by the pipe C⁴. The seat C⁵ is movable and also acts as a valve, closing against a seat as soon as the valve C⁶ quits it.
 120

In the position represented in Fig. 2 of the drawings the piston P³ receives equal pressure on both sides—that is to say, the left-hand face receives direct the action of the compressed air in pipe C⁴ and the right-hand 130 face is also in communication with the latter through the pipe C⁹ of cock R and pipe C¹⁰, the compressed air arriving by pipe C⁴, thus passing through pipes C⁸ and C⁹, which con-

duct it through the two cylinders. On turning cock R in the direction of the arrow to an angle of forty-five degrees the communication between the two pipes C⁹ C¹⁰ is cut off 5 and pipe C⁹ is placed by cock R in communication with the atmosphere. The right-hand face of the piston P³ is thus put in communication with the open air, and as the left-hand face of said piston continues to receive the 10 pressure from pipe C⁴ the equilibrium will be overcome and parts P³ C⁶ C⁵ will move together to the right, the valve C⁵ closing against its seat S and shutting off all communication between the compressed-air inlet C⁴ 15 and pipes C⁸ and C³. The pressure still remaining in the pipes continues to move piston P³ toward the right, and valve C⁶ is thus raised off C⁵, which forms its seat, so that the compressed air contained in pipes C⁸ C³ will 20 escape through the guide of valve C⁶ into the pipe C⁷, which leads to the exhaust. Both cylinders will in this manner be put in communication with the atmosphere. If cock R be returned to its initial position, Fig. 2, communication between the two pipes C⁹ C¹⁰ will be 25 reestablished and the right-hand face of piston P³ will receive the action of the compressed air supplied by pipe C, and owing to the difference in the areas of the surfaces acted on by the compressed air the parts C⁵ C⁶ and piston P³ will move to the left to their initial position, Fig. 2, and communication will thus be 30 reestablished between admission-pipe C⁴ and pipes C⁸ and C³. Thus by turning cock R 35 through forty-five degrees in the direction of the arrow both the cylinders are suddenly opened to the air, and by turning it through another forty-five degrees the pipe C⁹ remains open to the air, the pipe C¹⁰ is connected with C¹¹, and pressure is then admitted to the pipe to actuate the brakes, which are thereupon 40 applied.

Having described my invention, what I claim, and desire to secure by Letters Patent, 45 is—

1. In the system for compressed-air locomotive-carriages herein specified, having two cylinders adapted for working either compound

or at the same pressure in both cylinders, the means of controlling the working whereby a 50 single hand-wheel shaft A² is adapted to control the brakes, the variable cut-off to the high-pressure cylinder for compound working, the change from compound to simple working, and the progressive and variable admission of high pressure to the large cylinder; said shaft A² having keyed thereon a cam K acting on the lever L of brake-regulator; a toothed sector S' engaging a pinion p' 55 for actuating the variable-expansion valve of high-pressure cylinder; and a toothed sector S² engaging a pinion p⁶ which operates a slide-valve T⁷ for changing from compound to simple working and controlling the admission to the low-pressure cylinder, as described with 60 reference to the drawings.

2. In a compressed-air locomotive-carriage, the combination of high and low pressure cylinders adapted to work compound or direct, at will, the safety device N, connections between said cylinders and the safety device, a cock R under the control of the driver, said cock being adapted to operate said safety device to permit of suddenly cutting off the connection of the compressed-fluid supply with 70 the engine-cylinders and to establish communication between said cylinders and the atmosphere and to reestablish the normal communications of said cylinder, whereby the carriage may be suddenly stopped and again 75 started by the cock R.

3. In a compressed-air locomotive-carriage, the combination of two cylinders, means for supplying compressed air to said cylinders, a single hand-wheel for controlling such 85 means and means controlled by said hand-wheel to work said cylinders compound or direct at will and to control the brakes.

The foregoing specification of my improvements in compressed-air locomotive-carriages signed by me this 24th day of August, 1895. 90

JAMES TIBURCE FELIX CONTI.
